C. W. CLARKE.

BREAD SLICER.

APPLICATION FILED JUNE 23, 1919.

1,317,430.

Patented Sept. 30, 1919.

UNITED STATES PATENT OFFICE.

CHARLES WESLEY CLARKE, OF CHARLESTON, WEST VIRGINIA.

BREAD-SLICER.

1,317,430.

Specification of Letters Patent. Patented Sept. 30, 1919.

Application filed June 23, 1919. Serial No. 306,069.

To all whom it may concern:

Be it known that I, CHARLES W. CLARKE, a citizen of the United States, residing at Charleston, in the county of Kanawha and State of West Virginia, have invented certain new and useful Improvements in Bread Slicers; and I do hereby declare the following to be a full, clear, and exact description of the invention, such as will enable others skilled in the art to which it appertains to make and use the same.

This invention relates to a bread slicer, and particularly to a construction embodying a series of knives spaced from each other so as to cut a series of slices in a single movement of the device.

The invention has for an object to provide a novel and improved construction of the mounting for the slicing knives by which during their downward movement they also receive a lengthwise or drawing travel producing a shearing cut.

A further object of the invention is to provide a novel mounting for the knives comprising links slidably mounted at one end upon the base of the slicer and pivotally connected to the knives at their opposite end so that draft applied to the knife frames produces a downward and longitudinal movement of the knives.

Another object of the invention is to provide a novel and improved mounting for the knives by which they may be spaced at different distances apart by means of replaceable spacing collars disposed between the blades so that the thickness of the slices to be cut may be adjusted as desired.

Other and further objects and advantages of the invention will be hereinafter set forth and the novel features thereof defined by the appended claims.

In the drawing:

Figure 1 is a perspective of the invention;

Fig. 2 a detail vertical section through the knife supporting frame; and

Fig. 3 a similar view through the sliding support for the links.

Like numerals of reference refer to like parts in the several figures of the drawings. The numeral 10 designates the base of the machine which may be of any desired construction or configuration and the size thereof varied to accommodate the material to be sliced. As shown in the present illustration this base is provided at one

side with an upright stop 11 against which one end of the loaf 12 or other material may be abutted. For the purpose of retaining the loaf or object 12 against slipping movement during the cutting action, a series 60 of pins 13 may also be provided upon the base 10.

The slicing knives 14 may be of any desired construction and configuration and the number or character thereof varied as 65 found most convenient. These knives are mounted at their opposite ends upon cross rods 15 and spaced from each other by means of collars 16. These collars may be of various lengths and are interchangeable 70 so that the space between the knives and the consequent thickness of the slices to be cut may be varied. One rod 15 is pivotally mounted at its opposite ends in the upper ends 17 of the links 18 and the parts 75 19 threaded upon the opposite ends of the rod. The supporting links 18 just described are applied at one end of the series or gang of knives while at the opposite end a handle frame 20 is provided and has the opposite end members 21 mounted upon the rod and the intermediate member 22 similarly disposed. These parts 21 and 22 are connected to the rod or knives so as to form a 80 85 rigid attachment by which a downward and forward movement may be imparted to the entire structure when pressure is applied to the hand-hold 23.

The lower ends of the supporting links 90 18 are slidably mounted upon the base 10 in any desired manner, for instance, by means of the casings or housings 24 which have flanges 28 to embrace and support a sliding block 25 provided upon its upper surface with pivoting ears 26 between which the lower ends of the links are mounted by means of the cross pivot 27.

The construction and operation of the slicer will be apparent from the foregoing 100 description, and it will be noted that when pressure is applied to the free end of the knife frame, these knives are drawn toward the operator as they are forced downward thus producing a drawing or shearing 105 cut through the material to be sliced. This pivotal and sliding movement is effected by means of the links, the travel of which is limited by the housing so that the knives may travel from the full line position shown 110

in Fig. 1 to that indicated by dotted lines therein. While this invention has been particularly shown as applied for slicing bread and is adapted for that purpose, still it is 5 not confined thereto as the structure is capable of application for slicing any desired material and for varying the width and thickness of such slices as may be desired.

10 The specific construction of the knife connections and mounting for the links has been described and shown but the invention is not confined thereto as changes may be made within the scope of the following 15 claims.

What I claim is:—

1. In a slicer, a base, supporting links 20 slidably mounted thereon at one end, and a cutting knife pivotally connected to the opposite ends of said links.

2. In a slicer, a base, blocks slidably mounted thereon, supporting links pivoted at one end to said blocks, a connecting rod extending between the opposite ends of said 25 links, a series of spaced knives mounted upon said connecting rod, and a connecting rod extending between the opposite ends of

said series of knives for supporting the same.

3. In a slicer, a base, blocks slidably 30 mounted thereon, supporting links pivoted at one end to said blocks, a connecting rod extending between the opposite ends of said links, a series of spaced knives mounted upon said connecting rod, a connecting rod 35 extending between the opposite ends of said series of knives for supporting the same, and a yoked handle mounted upon said last-mentioned connecting rod.

4. In a slicer, a base, a housing mounted 40 thereon, a slide block disposed within said housing and retained thereby against vertical movement, a pivoting lug carried by said block, a supporting link carried by said lug, and a slicing knife pivotally connected to the upper end of said link. 45

In testimony whereof I have signed my name to this specification in the presence of two subscribing witnesses.

CHARLES WESLEY CLARKE.
